UNITED STATES PATENT OFFICE.

JOHN J. FORSTER, OF MIDLAND, PENNSYLVANIA, ASSIGNOR OF ONE-HALF TO
WILLIAM K. HART, JR., OF MIDLAND, PENNSYLVANIA.

WINDOW SHADE.

Application filed March 14, 1922. Serial No. 543,580.

To all whom it may concern:

Be it known that I, JOHN J. FORSTER, residing at Midland, in the county of Beaver and State of Pennsylvania, a citizen of the 5 United States, have invented or discovered certain new and useful Improvements in Window Shades, of which improvements the following is a specification.

My invention relates to improvements in 10 window shades, and consists in a shade journaled at an intermediate point of the height of the window opening together with means for drawing it at will in either direction, up or down, as need may be, to cover 15 any portion either of the upper or of the lower subdivisions of the window area. Minor and tributary features of invention will appear in the course of the ensuing specification.

20 In the accompanying drawings Fig. I is a view in elevation of a window frame, having a shade of my invention applied to it; Figs. II and III are views in vertical and medial section of the same assembly. Fig. 25 II shows the shade drawn down part way, and in the position shown in Fig. I; Fig. III shows the shade drawn up part way. Figs. IV and V are views to larger scale, showing in front and side elevation a certain fixture 30 which may advantageously be employed in carrying my invention into practice. Figs. VI and VII are fragmentary views in elevation similar to Fig. IV, and illustrating permissible modifications. It should be remarked of the drawings that, for purposes 35 of illustration the dimensions of the window frame and the diameter of the shade roller are intentionally exaggerated, that the structure may more clearly appear. This matter 40 may be dismissed without further comment.

The shade 1 borne on a suitable spring roller is journaled intermediate the extent of the window space. An endless cord 2, passing over pulleys 3 and 4 above and below 45 surrounds the shade; that is to say, one reach of the cord extends behind, the other in front of the shade. At one point in its extent, preferably in the front reach the cord is secured to the edge of the shade 50 (ordinarily hemmed and reenforced by a stick enclosed in the hem). Manifestly as the front reach or the rear reach of the cord is drawn downward the shade will be drawn downward or upward. Manifestly also the

shade, having previously been drawn, before 55 it can be drawn oppositely, should be allowed to roll up again under spring tension in usual manner.

Ordinarily the spring roller of a window shade is provided with a pawl-and-ratchet 60 latch, to secure it temporarily at the desired degree of extension. Having made the cord endless and arranged it as shown, I may and preferably do dispense with the usual latch just mentioned, and provide for anchoring 65 the cord in any position desired and so holding the shade extended. Suitable means of anchorage are indicated in Fig. I, where the upper pulley 3 is shown to be provided with a sheave having a helical runway. By 70 lateral manipulation of the cord the tension of the spring in the roller may cause the cord to bind between sheave and housing and so secure the shade until by tension and manipulation in opposite direction the cord 75 will run free again.

The fixtures which carry the roller may be set at any point desired, intermediate the ends of the window opening, and the pairs of fixtures may be made capable of resetting and of adjustment in position by suitable means. In Figs. I to V I show means which I find convenient and adequate. The journal blocks themselves 5 and 6, formed ordinarily of sheet metal, may be bolted 80 through slots in strips 7, which strips in turn are secured to the window frame. The bolting is such as to allow the blocks to slide longitudinally of the strips, and also to allow them to turn pivotally. The 85 journal blocks are provided with tongues 8 adapted to enter notches formed along the edges of strips 7, and springs 9 are provided, so arranged that their tension is exerted to hold the blocks 5 and 6 with 90 tongue 8 in engagement with a notch. The blocks 5 and 6 are further provided with thumb rests 10, by which they may be turned 95 pivotally against the tension of the springs to release the tongues 8 from the notches in the edges of strips 7. Any desired numbers of pairs of notches may be formed in the opposite strips 7. The two journal blocks 5 and 6 being secured by the tongue and notch 100 engagement described, their position may be changed by turning them pivotally against spring tension and shifting them along strips 7 to the desired new position and then 105

releasing them to turn under spring tension and make again the same engagement with another pair of notches.

Figure VI shows that instead of vertically adjustable journal blocks, a succession of journal blocks 5^a may be set along the length of the window frame and between any opposite pair of such journal blocks the shade roller may be hung, and it may be changed from pair to pair as may be desired. Figure VII shows at 5^b a journal block which may be screwed to place at any point desired longitudinally of the window frame.

My invention is applicable in all sorts of places, but I find it to be peculiarly useful when applied to the windows of school rooms and other places of public gathering.

I claim as my invention:

1. In a window shade structure the combination with a window opening of a shade having a spring roller journalled at a point intermediate the length of the opening, opposite fixed abutments arranged beyond the range of shade travel, and an endless cord movable over said abutments and encircling said shade, said cord being secured at one point to the edge of the shade.
2. In a window shade structure the com-

bination with a window opening of a spring roller journalled at an intermediate point in the length of such opening, a shade secured at one edge to said roller, opposite abutments arranged beyond the range of shade travel, an endless cord secured at one point to the otherwise free edge of the shade, passing completely around shade and roller and over said abutments, and means of which one of said abutments forms part for securing said cord from free running in response to tension of said spring roller.

3. In a window shade structure the combination with a window frame of a pair of journal blocks adjustably carried in said window frame at points intermediate the length thereof, a spring roller shade borne by said blocks, fixed abutments borne by said frame in the ends thereof and an endless cord secured at one point to the otherwise free edge of said shade, passing entirely around said shade and passing over said opposite abutments.

In testimony whereof I have hereunto set my hand.

JOHN J. FORSTER.
